INVENTOR.

BY *J. A. Bishop*
ATTORNEY

UNITED STATES PATENT OFFICE.

ELLA DIEFENBACHER, OF NEW PHILADELPHIA, OHIO.

LINGERIE PIN.

Application filed May 24, 1922. Serial No. 563,245.

To all whom it may concern:

Be it known that I, ELLA DIEFENBACHER, a citizen of the United States, residing at New Philadelphia, in the county of Tuscarawas and State of Ohio, have invented a new and useful Lingerie Pin, of which the following is a specification.

This invention relates to lingerie clasps and has for its principal object the construction of a clasp of this type which not only has the usual features of a clasp when fastened in position but which is also provided with means for retaining the clasp in position upon the apparel of the wearer, should the said clasp become unfastened accidentally while in use.

In the drawings in which similar numerals of reference indicate corresponding parts;

20 Fig. 1 is a perspective view showing one of my clasps in use.

Fig. 2 is an enlarged perspective showing my clasp opened.

Fig. 3 is a side elevation of a clasp in which a hinge is employed for joining the two movable arms.

Fig. 4 is a similar view showing a clasp made from a single piece of metal.

I am aware that numerous and varied 30 clasps have been designed and are now employed for the purpose of attempting to secure the shoulder straps of a woman's lingerie against slipping from the shoulder and hanging over the outside of the arm.

35 A common fault however, with all the devices of this class heretofore designed, is their failure to remain in position or to hold the lingerie straps in position, should the snap, hook or other means of securing the 40 said clasp become unfastened.

Various clasps are now made in which 45 teeth carried by the opposite jaws of the clasp are brought into engagement with the straps of the underwear when the said clasp is fastened in position. Other forms employ corrugations or in-turned flanges to grip the straps when the clasp is closed. These will, of course, all prevent the lingerie straps from becoming displaced and also 50 eliminate the possibility of the clasp itself slipping, just as long as the said clasp re-

mains fastened and the teeth, corrugations or other protuberances are in forced engagement with the clothing. But, should the fastening means used on the clasp inadvertently become opened, the clasp will immediately drop off and allow the straps to slide out of position.

At 1 I have shown the upper arm of a clasp and at 2 the lower arm thereof, the 60 said arms being joined together at one end as by the hinge 3. At the opposite end of the arm 1 is formed integral with the said arm one member 4 of a snap fastener, the interfitting member 5 of which is formed on the free 65 extremity of the arm 2.

Extending inwardly from a point adjacent the hinged end of the arm 2 is an elongated, sharpened prong or pin 6 which projects upwardly from the arm 2 to a point about 70 midway between the arms 1 and 2 when the clasp is fastened, and then extends toward the free ends of the said arms in a line substantially parallel with the top face of the arm 2.

75 Fig. 4 illustrates a clasp which is stamped entirely from one piece of metal, the said metal having sufficient spring therein to spread the arms a proper distance apart without the use of a hinge.

Fig. 4 illustrates a clasp which is stamped entirely from one piece of metal, the said metal having sufficient spring therein to spread the arms a proper distance apart without the use of a hinge. 80 In the use of my clasp, the free end of the arm 2 will be inserted beneath the shoulder straps of the underwear and the said straps impaled on the prong or pin 6. The upper arm 1 is brought down and the members 4 and 5 of the fastener are snapped together. It will be obvious that it is now impossible for the clasp to slide on the straps. Should the members 4 and 5 of the clasp accidentally become separated and allow the clasp to open, 90 the pin 6 will still remain fast in the straps and thereby prevent the clasp from becoming displaced.

Having now described my invention what I claim is:

1. A device of the character described comprising a pair of relatively movable arms hingedly secured together at one extremity, one member of a snap fastener carried by each of said arms at the free extremity thereof, said members being arranged to contact to fasten the free ends of said arms to-

gether and a prong extending longitudinally between said arms and attached to the lower of said arms.

2. A lingerie pin comprising a pair of relatively movable arms, one member of a snap fastener carried at the free extremity of each arm, said members being arranged

to co-act to fasten the free ends of the arms together, and a prong extending longitudinally between the arms.

In testimony that I claim the above, I have hereunto subscribed my name.

ELLA DIEFENBACHER.
